Primary Examiner — John Windmuller*Assistant Examiner* — John R Yeh(74) *Attorney, Agent, or Firm* — Beeson Skinner Beverly, LLP(57) **CLAIM**

The ornamental design for a grill cleaning tool, as shown and described.

DESCRIPTION

FIG. 1 is a front perspective view of a grill cleaning tool showing our new design;

FIG. 2 is front elevational view thereof;

FIG. 3 is a right side elevational view thereof;

FIG. 4 is a rear elevational view thereof;

FIG. 5 is a top plan view thereof; and,

FIG. 6 is a bottom plan view thereof.

The broken lines in FIGS. 1 to 6 show a loop of rope and an opening in the handle of the grill cleaning tool for receiving the loop of rope, both of which form no part of the claimed design.
